INTERNAL GRINDING AND HONING
MACHINEBror E. Hanson, Worcester, Mass., assignor to The
Heald Machine Company, Worcester, Mass., a
corporation of Massachusetts

Application August 29, 1940, Serial No. 354,736

5 Claims. (Cl. 51—3)

The present invention relates to a machine for grinding and honing the bores or interior surfaces of hollow workpieces; the invention resides in the provision of a simple and compact machine organization whereby with a single chucking of the workpiece, the latter's bore can be subjected, either successively or selectively, to a precision grinding operation and to a honing or lapping operation. In one of its aspects, the invention provides the honing apparatus in the form of an attachment readily applicable to a conventional type of internal grinding machine.

Other and further objects and advantages of the invention will more fully appear from the following detailed description thereof, taken in connection with the accompanying drawing in which

Fig. 1 is a front elevational view of a machine embodying the invention.

Fig. 2 is a fragmentary larger scale plan view showing the positions of the associated grinding and honing devices, when the former is in operative relation to the workpiece bore.

Fig. 3 is a sectional view substantially on line 3—3 of Fig. 2, but showing the conditions which prevail when the honing device is operative on the workpiece bore.

Like reference characters refer to like parts in the different figures.

Fig. 1 shows a machine providing the essential elements of a conventional internal grinding machine, said machine including a suitable base 1 which has longitudinal ways, not shown, for the back and forth reciprocations of a table 2. Such table movement serves to obtain the longitudinal traverse of the workpiece bore by the grinding wheel; to this end the table may carry either the work or the wheel—with the other of said parts mounted on a stationary bridge 3 which spans the ways, not shown, whereon the table slides. In the illustrated arrangement, the table 2 carries the grinding wheel 4, the latter being secured to a rotary spindle 5 which overhangs and is suitably journaled in a tool carrier 6 carried by a cross-slide 7 on the table 2. On its other end said spindle 5 carries a pulley 8 whose driving belt, not shown, produces the desired high speed rotation of the grinding wheel for the grinding operation on the bore of each workpiece A. The latter is received and held in a chuck or other suitable work-holding device 9, whose hollow shaft 10 is rotatively mounted in a workhead 11 on the bridge 3; the chuck shaft has a pulley 12 whose belt, not shown, imparts rotation to the workpiece A dur-

ing the grinding and honing operations on the bore thereof.

The movements of table 2 to carry the grinding wheel into and out of the workpiece bore and to reciprocate said wheel for a grinding traverse of the bore's surface, may be obtained in any well-known manner, as by use of the fluid pressure controlling and reversing mechanism disclosed by Heald and Guild Patent No. 1,582,468 dated April 27, 1926. Such mechanism of and by itself forms no part of the present invention and need not be described in detail; it is sufficient to point out that the grinding reciprocations of the table 2 are controlled by a pair of spaced adjustable dogs 13 and 14 thereon, arranged to engage alternately with a member 15 whose movements are transmitted to a reversing valve, not shown, in the fluid pressure system, said valve causing the fluid under pressure to be admitted first to one side and then to the other side of a cylinder and piston unit, not shown, having an actuating connection 2' with the table 2. In order to shift the grinding wheel transversely into and out of cutting relation to the surface of the workpiece bore, and to provide for a gradual feed of said wheel, during the grinding operation, into said surface until the desired size of bore is obtained, the cross slide 7 carrying the wheelhead is subject to movement, either manually, or automatically in any well known manner, by the usual feed screw 1', which carries a handwheel 1''.

According to my invention the tool carrier 6, in order to provide support for the honing or lapping devices hereinafter described, may have an extension or quill 6' surrounding the overhanging portion of wheel spindle 5. Said member 6' on its outer upper surface and on its outer lower surface provides the pairs of lugs 16, 16 and 17, 17; attached to these lugs in any suitable manner are the two pairs of flat leaf spring members 18, 18 and 19, 19 all projecting laterally from the quill 6' in the same direction, i. e. away from that side of the grinding wheel 4 which makes contact with the workpiece bore. To the outer ends of all four of said leaf springs 18, 18, 19, 19 is attached, in any suitable manner a plate 20, the latter as shown in Fig. 2 being thus disposed and held in a vertical plane which is substantially offset, laterally, from that side of grinding wheel 4 which is opposite said wheel's line of contact with the workpiece bore—this arrangement and spacing thus permitting said plate 20 to extend well beyond the quill 6' and

to occupy at its outer or free end the same transverse zone as that occupied by the grinding wheel.

On the spindle 5 of the grinding wheel beyond the quill 6' is secured or formed a cam 21 providing an encircling helical track or groove 22. The plate 20 on its inner surface, substantially in the transverse zone occupied by said cam, provides a hollow boss 23 whose bore, substantially at right angles to the grinding wheel spindle axis and extended through the plate 20, receives slidably a pin 24 whose outer end beyond plate 20 carries an enlargement or knob 25 by which to move said pin either inwardly, to operatively engage its inner end with groove 22, or outwardly, to dispose said pin in its inoperative position. Spaced grooves 26 and 27 on said pin are arranged to be selectively engaged by a spring-pressed ball 28 provided in the boss 23, adjacent to and projecting into the latter's bore, so as to yieldingly hold the pin either in its operative position, or its inoperative position, as desired. On the outer surface of plate 20, preferably in the transverse zone of the grinding wheel 4, is provided a suitable holder 29 for the reception and retention of a honing or lapping stone 30, the latter preferably being substantially as long as the grinding wheel is thick. Said stone near each end preferably seats against a yieldable member or spring 31, and has a certain limited freedom of movement within the holder 29, to permit it to adjust its position in accordance with its outer surface's engagement with the work. Such engagement as shown in Fig. 3 is made with that portion or side of the workpiece bore which is diametrically opposite to the side or portion engaged by the grinding wheel 4 (Fig. 2).

In the operation of the machine, the grinding of the workpiece bore to the desired size by the wheel 4 takes place in the usual manner, preferably with the pin 24 in its inoperative position (Fig. 2); that is to say, the operator by manipulation of the table control lever 32, Fig. 1, causes the table 2, in the manner set forth in the afore-said Heald and Guild Patent 1,582,468, to move leftwards from the rest position shown in Fig. 1, to carry the grinding wheel into the workpiece bore, this movement positioning the dogs 13 and 14 on opposite sides of the member 15, so that the table thereafter reciprocates in a grinding range, moving the wheel 4 back and forth from one end to the other of said bore. The hand wheel 7' may be employed to cross-feed the wheel quickly into contact with the workpiece bore (Fig. 2) and the grinding then proceeds with progressive cross feeding of the wheel (either manual or automatic) by the screw 7 until the bore is enlarged to the desired size. Then, by turning the screw 7 oppositely, the wheel is backed off from the ground surface, such movement causing the stone 30 to approach correspondingly a diametrically-opposite portion of said surface. With the pin 24 now pushed inwardly to engage the cam groove 22, a very short and rapid reciprocation, of the order of a vibration, is set up in the stone-carrying structure by the rotation of spindle 5—the spring supports 18 and 19 for said structure flexing readily for this purpose.

Thus the vibrating stone 30, brought into contact with the bore of the rotating workpiece by the back off movement of the grinding wheel 4 from its contact with said bore, performs a complete honing operation over the entire surface of

the bore from end to end, since the reciprocations of the table 2 carry the vibrating hone, the same as they do the rotating grinding wheel, back and forth over the entire length of the bore, with the work-piece rotation at the same time subjecting all portions of the bore's surface to the action of said stone.

I claim:

1. In a machine of the class described, a rotary workholder, a rotary grinding wheel for operation on the bore of a workpiece in said workholder, means for imparting a relative axial reciprocation to said parts to traverse said wheel from one end to the other of said bore, a honing member flexibly connected to the support of said wheel and adapted by said reciprocation to make an end-to-end traverse of said bore, cross-feed means operable in one direction to engage said wheel with said bore's surface and to space said honing member therefrom, and operable in the other direction to engage said honing member with said bore's surface and to space said grinding wheel therefrom, a cam rotating with said grinding wheel and means for detachably engaging said cam with said honing member to vibrate the latter by flexure of its connection during its operation on said bore.

2. In a machine of the class described, a rotary workholder, a rotary grinding wheel for operation on the bore of a workpiece in said workholder, a spindle whereon said wheel is carried, a head or support wherein said spindle is journaled, a honing member flexibly connected to said head or support, means for cross-feeding said head or support in opposite directions to selectively engage said wheel and said honing member with the workpiece bore; means for imparting a relative reciprocation between said work holder and said head or support, whereby the tool selectively made operative by said cross-feed means effects an abrasive traverse of said bore from end to end, a cam on said spindle, and means for detachably engaging said cam with said honing member to vibrate the latter by flexure of its connection during its abrasive traverse of said bore.

3. In a machine of the class described, a base, a table reciprocatable on said base, a rotary workholder arranged on one of said parts and a tool carrier arranged on the other of said parts, a rotary grinding wheel projecting from said tool carrier for operation on the bore of a workpiece in said workholder, a honing member flexibly connected to said tool carrier and occupying substantially the same zone, transversely of said machine, as said grinding wheel, means for cross-feeding said tool carrier in one direction to operatively engage said grinding wheel with the workpiece bore, means for cross-feeding said tool carrier in the opposite direction to operatively engage said honing member with the workpiece bore, means for reciprocating said table whereby the tool selectively made operative by said cross-feed means effects an abrasive traverse of said bore from end to end, a cam rotating with said grinding wheel, and means for detachably engaging said cam with said honing member to vibrate the latter by flexure of its said connection to said carrier, during its abrasive traverse of said bore.

4. In a machine of the class described, a rotary workholder, a tool carrier, a rotary spindle journaled in said carrier, a grinding wheel on said spindle for operation on the bore of a workpiece in said workholder, a honing member, a

flexible member supporting said honing member from said tool carrier, means for crossfeeding said tool carrier in one direction to operatively engage said grinding wheel with the workpiece bore, means for crossfeeding said tool carrier in the opposite direction to operatively engage said honing member with the workpiece bore, means for relatively reciprocating said workholder and tool carrier whereby the tool selectively made operative by said crossfeed means effects an abrasive traverse of said bore from end to end, a cam rotating with said grinding wheel, and means for detachably engaging said cam

with said honing member to vibrate the latter by flexure of its supporting member, during its abrasive traverse of said bore.

5. A honing attachment applicable to the wheelhead of an internal grinding machine, comprising a honing member, a flexible connection supporting said honing member in diametrically opposed relation to the grinding wheel of said machine, a cam rotating with said wheel, and means for detachably engaging said cam with said honing member to procure the latter's vibration by flexure of said connection.
